UNITED STATES PATENT OFFICE.

FRED STARR, OF SACRAMENTO, CALIFORNIA.

ROLLER-CLUTCH LIFTING-JACK.

1,174,363.

Specification of Letters Patent. Patented Mar. 7, 1916.

Application filed February 24, 1914. Serial No. 820,547.

To all whom it may concern:

Be it known that I, FRED STARR, a citizen of the United States, residing at Sacramento, in the county of Sacramento and State of California, have invented certain new and useful Improvements in Roller-Clutch Lifting-Jacks; and I do hereby declare the following to be a full, clear, and exact description of the invention, such as will enable others skilled in the art to which it appertains to make and use the same.

This invention relates to improvements in lifting jacks, and has for its object the provision of such a device having the novel features of construction and operation, as hereinafter set forth.

The invention is illustrated in the accompanying drawing, in which,

Figure 1 is a perspective view of the improved jack, a portion of the casing of the same being broken away to show the interior mechanism; Fig. 2 is an enlarged view of the upper extremity of the jack showing more clearly the releasing mechanism.

Referring to the drawing, the frame of the jack is indicated at A, and may be of any appropriate shape and construction suitable for housing the operative parts of the jack. Slidably mounted in the casing A is the lifting bar B, provided at its lower extremity with a projecting toe C, adapted to support, raise or lower a weight when the bar B is actuated. The casing A is provided with an opening V to accommodate the toe

C. The upper extremity of the bar B is provided with a cap C secured to the said bar by any suitable means, such as the screw E. The cap D, in the lowermost position of the bar B, abuts the top of the casing A, and thereby prevents further downward movement of the bar with respect to the casing. The cap D also constitutes a supporting head for the object to be acted upon by the jack.

Situated interiorly of the casing is a block F, preferably of metal and provided with a recess adapted to accommodate the bar B. The provision of the recess forms an arm G, which engages the outer surface of the bar B. The inner surface of the recess in block F facing the inner surface of the bar B is inclined, as shown at F'. A plate M, secured to the top of the block F, is provided with an opening L through which a wire K is passed and bent at its upper extremity over the surface of the plate M to prevent

the same from slipping through said opening. The lower extremity of the wire K supports a roller H in any suitable manner, such as by providing said roller with a circumferential groove, in which the looped extremity of the wire K is adapted to engage. A coiled spring O, preferably conical in shape, is interposed between the plate M and the roller H, and tends to force the latter downwardly between the inner face of the bar B and the inclined surface F'. The above-described manner of mounting the roller H is merely exemplary, as obviously the same can be mounted in numerous ways to produce the same result.

A plate X may be secured to the side of the block F to constitute a closure for the interior mechanism thereof.

A handle socket P is pivotally mounted on the casing A, preferably by means of a bolt R and coöperating nut S. The said socket is provided with a heel portion Y adapted to engage in an appropriately formed opening in the block F, whereby pivotal movements of the socket P around the axis R will produce longitudinal movements on the block F. The socket P is provided with a suitable recess Q, in which the actuating lever may be inserted.

Mounted on the casing 1 and projecting into the lower portion of the recess in the block F is an extension T, constituting a trip for the roller H, as will be hereinafter described.

The upper part of the casing is provided with an inwardly projecting portion 1 presenting an inclined surface similar to that provided on the block F. A roller 2 is interposed between such inclined surface and the inner surface of the bar B, and is supported in a manner similar to that described in connection with the roller H, to wit, by a wire 12, the lower extremity of which is looped around the body of the roller and engages in a peripheral recess 9.

The upper extremity of the wire 12 passes through an opening 6 in a removable cover plate 14 held in place by a screw 10, and is looped, as shown at 12', to engage the cross pin 7 of a pivoted releasing lever 3. The said lever 3 is pivoted to standards 4, 4', as clearly shown in Fig. 2 at 5, 5'. The cross pin 7 is disposed on the opposite side of the pivots 5, 5' from the actuated extremity of the lever, so that when the outer extremity of the lever 3 is depressed, the pin 7 is

raised, thereby lifting the supporting wire 12 and the roller 2. A spring 11 similar to that used in connection with the roller H reacts at one extremity against the bottom of the plate 14, and at its other extremity against the roller 2, thereby holding the roller 2 in its lowermost position, and the outer extremity of the lever 3 in its raised position.

10 The operation of the apparatus is as follows:—A downward force applied to the actuating handle in the socket P raises the block F, and the inclined surface F' thereof wedges the roller H between the same and 15 the inner surface of the bar B. The said surface F', roller H, and arm G coöperate in gripping the bar, and an upward movement of the block F, therefore, results in an upward movement of the bar B. As the 20 actuating lever is raised and the block F lowered, the bar B in tending to lower, wedges the roller 2 between the inclined surface of the portion 1 and the inner face of the bar B. The bar B is thereby prevented 25 from lowering and is held in the position to which it was elevated by the raising of the block F. When the block F lowers with the raising of the actuating lever, the inclined surface F', roller H, and arm G are inoperative, since no wedging action of the roller H results in a downward movement of the 30 block F. The next downward movement of the actuating lever will cause the block F, roller H, and arm G to grip the bar B at a 35 lower point, and the lifting action, as above described, will be repeated, the projecting portion 1 and roller 2 serving at each actuation of the lever to hold the bar B in its elevated position. In order to permit the 40 bar B to lower, the actuating lever is depressed, thereby raising the block F and loosening the roller 2. The lever 3 is then depressed, which elevates the roller 2, and prevents a wedging action between the same 45 and the projection 1, when the bar B is lowered. The actuating lever is then raised,

thereby lowering the block F. As the roller 2 is held in its raised position, the bar B is free to lower with the block F. As the roller H lowers with the block F, the projection T engages the same, and thereby trips the roller to permit further downward movement of the bar B.

Obviously, many modifications and changes can be made in the details of construction, 55 without departing from the spirit of the invention, as defined in the accompanying claim.

What I claim is:—

A lifting jack comprising a casing, a 60 slideable lifting bar mounted therein, an actuating block slidably mounted on said bar, said block presenting an inclined surface to one face of said bar, a roller interposed between said inclined surface and said face of 65 the bar and provided with a circumferential recess, a wire engaging in said recess and supported at its upper end from said block, a spring encircling said wire and tending to wedge said roller between said inclined 70 surface and the face of said bar whereby the bar is lifted unitarily with the block when the latter is raised but permitted to remain stationary when the block is lowered, means to raise and lower said block, an element presenting a second inclined surface to said bar, a second roller interposed between said surface and one face of said bar and provided with a circumferential recess, a wire engaging in said recess, a trip lever 75 to which the upper end of said wire is connected, and a second spring encircling said last-named wire tending to wedge said roller between said surface and said face of the bar whereby said bar is held stationary when 80 the block is lowered.

In testimony whereof I affix my signature, in presence of two witnesses.

FRED STARR.
